INSULATED ROOF

William D. Thompson, Birmingham, Mich., assignor, by mesne assignments, to Standard Railway Equipment Manufacturing Company, a corporation of Delaware

Application April 5, 1937, Serial No. 135,173

4 Claims. (Cl. 108—5.2)

The invention relates to railway cars such as refrigerator cars which are provided with thermal insulation for the walls and roof thereof. More particularly the invention relates to the means for insulating the roof or ceiling of the car, and has for its object facilitating the installation of such insulation and protecting it from injury during service.

In the present state of the art it is usual to support the ceiling insulation from the roof or roof frame. This requires the installation of the insulation subsequent to the placing of the frame on the car and with certain types of roof, where the frame or supporting trusses are integral with the roofing sheets, the placing of the insulation is rendered difficult. It is, therefore, one of the objects of my invention to obtain a construction in which the supporting of the ceiling insulation is entirely independent of the roof or its frame. With this and other objects in view, the invention consists in the construction as hereinafter set forth.

In the drawings:

Figure 1 is a cross section through one-half of the roof portion of a railway car provided with my improved insulating means;

Figure 2 is a longitudinal section;

Figure 3 is a plan view with one-half of the roof removed to show the underframe for supporting the insulation;

Figure 4 is a cross section illustrating the detachable connection between the roof and the car and also the support for the insulation;

Figure 5 is a side elevation of Figure 4;

Figures 6 and 7 are views similar to Figures 4 and 5 illustrating a modified construction.

My improved ceiling insulation may be applied to cars having any desired type of roof covering, but as specifically illustrated the roof is of the so-called "two-plane" type. In this, the use of separate carlines is dispensed with and the roof trusses are formed as an integral part of the weatherproofing roofing sheets. In detail, A are the roof units comprising sheets extending from eaves to eaves with a central upper plane portion A' and lower plane portions A² on opposite sides thereof and intermediate substantially vertical portions A³. The edges of adjacent sheets are welded or otherwise secured to each other as indicated at A⁴. At the eaves both upper plane and lower plane portions are turned downward to merge into a single vertical plane portion B, preferably reinforced by a parallel member C. To permit of readily attaching and detaching the roof from the car frame, it is secured thereto by

means of bolts D which are connected with and project outward from the side plate E of the car frame. This side plate is shown as of a Z-bar cross section, the bolts being secured to the upwardly extending flange E' thereof. The portions B of the roofing sheets and also the reinforcement C thereof are provided with vertical slots F which register with the bolts D, said slots terminating at their upper ends in circular enlargements F', which latter are adapted to receive securing members sleeved on the bolts. As shown in Figures 4 and 5, the securing members are collars G having flanges G' for engaging the circular portions F' and surrounding portions G² for bearing upon the portion B. Nuts H engaging the bolts D are then used for clamping the members G in position. In the modified construction shown in Figures 6 and 7 in place of the nut H, the bolt D' has placed thereon a sleeve I having a head I' at its outer end and a collar I² which is slidable on the sleeve into and out of engagement with an aperture H'. The outer end of the bolt is then riveted to permanently secure the sleeve I, and a U-shaped wedge member J is inserted between the head I' and the collar I². Thus this wedge member serves to hold the collar in locking engagement with the circular recess F' and also to clamp the portion B to the side plate E'.

A car roof constructed as above described can be readily attached to or detached from the frame of a car which facilitates the original placing and the repair of the ceiling insulation.

The ceiling insulation is supported entirely independent of the roof structure through the medium of a series of cross members attached at their opposite end to the side plates E of the car frame. As shown, bracket members K are welded or otherwise secured to the side plates E to project inward therefrom and to these are secured the ends of metallic cross members L, preferably of inverted channel cross section with laterally extending foot flanges L'. Within the channels are placed wooden filler strips M which extend downward some distance below the flanges L' and are secured by bolts M'. To the strips M is secured a ceiling N, preferably formed of match boards and with a liner panel N' slightly spaced from the boards by strips N². These parts may be nailed or otherwise secured to said strips M. A layer of insulating material O, preferably hair felt, is then placed in the spaces between the strips M, and is marginally secured by strips P. These strips are placed beneath the flanges L' of the members L compressing the marginal por-

tions of the felt and securely holding the same from displacement. A second layer of felt O' is then placed above the layer O and is carried over the members L. This is secured by cap members 5 Q which may be clamped by upward extensions of the bolts M'. Thus as shown the threaded ends of these bolts M' have nuts M² thereon for clamping the strips M to the members L, and nuts M³ for clamping the caps Q upon the felt 10 layer O'.

At the sides of the car the ceiling N engages mortised wooden strips R which are attached to and supported from the brackets K by means of bolts R'. These strips R also form the means 15 for securing the insulation for the sides of the car which, however, forms no part of the present invention.

Where the car is provided with a hatch opening the hatch frame S may be placed between a 20 pair of cross members L and secured thereto by angle brackets S'. As shown, the angle brackets S' are attached to the members L by the bolts M' and to the frame S by bolts S². The insulation O' is carried upward along the side of the 25 frame S and is clamped at its upper end by a strip S³.

The ceiling insulation constructed as above described is entirely independent of the roof and may be placed in position before the roof is 30 attached to the car frame. Furthermore, by reason of the quick detachment connections between the roof and the frame, the former is easily removed at any time should it be necessary to repair the insulation. The insulation and 35 its supports are also freed from any roof stresses.

What I claim as my invention is:

1. In a car having metallic side plates and a roof removably supported thereon, of angle brackets rigidly attached to and projecting inward from said side plates, metallic channel 40 bars secured to said angle brackets and extending transversely of the car between the opposite side plates thereof, wooden strips secured in the channels of said bars and extending below 45 the same, a ceiling secured to the underside of said strips, a layer of insulating material extending between adjacent strips and marginally secured thereto, and a second layer of insulating material extending over said first layer and 50 said channel bars and clamped to the latter.

2. In a car having side plates and a roof removably supported thereon, inverted channel

bars connected to and extending between said side plates and independent of said roof, said bars having foot flanges on opposite sides thereof, wooden filler strips engaging the channels of said bars and projecting below the same, a ceiling secured to the underside of said filler strips, insulating material arranged between adjacent strips, strips placed beneath said foot flanges and engaging the marginal portions of said insulating material to clamp the same, a second layer 10 of insulating material extending over the first layer thereof and also over said channel bars, and caps for clamping said second layer of insulating material to said channel bars.

3. In a car roof having side plates and a roof removably supported thereon, inverted channel 15 bars connected to and extending between said side plates independent of said roof, said bars having foot flanges on opposite sides thereof, a wooden filler strip engaging the channels of said bars and projecting below the same, bolts for 20 securing said filler strip to said channel bars, a ceiling secured to the underside of said filler strips, insulating material arranged between adjacent strips, strips placed beneath said foot 25 flanges and engaging the marginal portions of said insulating material to clamp the same, a second layer of insulating material extending over the first layer thereof and also over said channel bars, caps for clamping said second 30 layer of insulating material to said channel bars, upward extensions of said bolts passing through said caps, and nuts engaging said upward extensions for clamping said caps in position.

4. In a car, the combination with the side 25 plates thereof, of a roof having means for quick attachment to and detachment from said side plates, comprising depending eaves flanges overlapping said side plates, said flanges having apertures therein with entrance slots to said 40 apertures from the lower edge of the flange, bolts projecting laterally from said side plates registering with said apertures and adapted to enter the same through said slots, fasteners sleeved on said bolts engaging said apertures, 45 and clamping means for said fasteners; a ceiling supported from said side plates independent of said roof and an insulating means supported by said ceiling accessible upon the removal of said roof.

WILLIAM D. THOMPSON.
